UNITED STATES PATENT OFFICE.

MARCELLUS B. CLARKE, OF CANTON, OHIO.

PROCESS OF MAKING RUBBER WATER-BOTTLES.

1,207,372.

Specification of Letters Patent.

Patented Dec. 5, 1916.

Application filed October 20, 1915. Serial No. 56,976.

To all whom it may concern:

Be it known that J. MARCELLUS B. CLARKE, a citizen of the United States, residing at Canton, in the county of Stark and State of Ohio, have invented a certain new and useful Improvement in Processes of Making Rubber Water-Bottles, of which the following is a full, clear, and exact description, reference being had to the accompanying drawings.

My Patent No. 1,117,327, issued November 17, 1914, shows, describes and claims a rubber water bottle wherein the filling funnel and neck is made integral with the side walls of the bottle, and there are upwardly extending ears from such side walls having originally an opening between them which is ultimately closed by intimately uniting the ears together. Such a bottle may have only one pair of ears located at diametrically opposite sides, and the ears may be retained in the finished bottle, or they may be trimmed off after being intimately united.

The present invention is concerned with the process or method of making such a bottle as described, this process involving the molding over a core or mandrel of the two sides and the neck and funnel of the bottle, together with separated flanges aligned with the neck and sides, the core being afterward removed through the space between the flanges, and the flanges thereafter united. Such process obviates the necessity of removing the core through the bottom of the bottle, as has been a frequent practice heretofore, and thus results in enabling the bottle to be most secure where it has to bear the greatest strain, namely; along the lower edge.

My invention is illustrated by the drawings hereof, and is hereinafter more fully described and the essential steps are summarized in the claims.

In the drawings, Figure 1 is a front elevation showing a bottle made by my process after vulcanization but before the ears are trimmed off; Fig. 2 is a view of the upper portion of the bottle before the ears have been secured together and thus showing the opening through which the core is removed, the opening in this case being made through both shoulders of the bottle; Fig. 3 is a view of the upper portion of the finished bottle partly broken away to show the thimble applied within; Fig. 4 is a cross section through the neck of the bottle as indicated

by the line 4-4 in Fig. 3; Fig. 5 is a perspective view of a bottle made by the same process where the slit through which the core is removed is confined to one shoulder of the bottle, the ear on the other shoulder being a solid flange or dummy for appearance' sake and stiffening purposes; Fig. 6 is a sectional perspective view of such bottle as molded and before the ears are secured together; Fig. 7 is a perspective view of such bottle after the ears are secured together and before they are trimmed off; Fig. 8 is a cross section through the funnel of such bottle adjacent to the top; Fig. 9 is a side elevation of a mandrel which may be employed; Fig. 10 is a horizontal section of such mandrel on the line 10-10 of Fig. 9 looking downwardly.

In each of the views 1 to 8 inclusive, 6 designates the sides or body portions of the bottle, 7 the neck portion, and 8 the funnel portion, and 9 the tabs and 10 corrugations which may be formed on the inside of the neck portion.

In order to permit the core to be withdrawn from such a bottle without opening the bottom or sides, the neck and funnel portions of the blank are interrupted on one or both sides to make separable flaps which are 85 united or continuous at their lower ends with the opposite sides of the body, but which are free or disconnected from each other on one or both sides of the neck above or beyond a slot extending across the top 90 of the bottle. In other words, instead of making the neck and funnel portions continuous and circular, they are split or left open, thus producing a slit which extends down the shoulder of the bottle a sufficient 95 distance to allow the removal of the core.

At the time the blank or body is made, as above indicated, each side of the neck and funnel is provided with an extension or flange, indicated at 12, and the corresponding side of the bottle has, at the shoulder, an extension or flange 13. The core for the interior of the blank and the mold within which it is made are suitably constructed for the above purpose, and the resulting blank 100 is seamless and is closed at all points, except the elongated opening at the top of the bottle.

In fashioning the bottle, it is preferably formed on a core provided with an extended portion, shaped similarly to the ears or flanges and extending between them,

whereby they are kept separated until the bottle has been given what is known as a partial semi-cure. After the first or semi-cure, the bottle and core are removed from 5 the mold and the bottle is stripped from the core, this operation being easily accomplished by reason of the slit through the top of the bottle.

After the removal of the blank from the 10 mold and its removal from the core, the metal thimble is applied. This is done by placing the thimble, which is indicated at 14, between the separated portions of the neck, rubber gum or cement being applied around 15 the edges 12 and 13, as well as around the thimble. The neck portions are then closed against the thimble. The flanges or edges 12 and 13 are lapped or pinched or worked together by hand to form a complete tube or 20 funnel and close the side opening or joint, thereby completing the funnel, the neck around the thimble and the top of the bottle. The bottle is then subjected to a final cure in a suitable vulcanizing mold which intimately 25 unites the flanges or ears to close the opening. At the same time the bringing together of the opposing faces of the ears serves to complete the annular formation for the filling funnel, and also serves to hold the stopper 30 receiving nipple in position. After the final cure, the united flanges are trimmed or otherwise treated, as desired.

The flanges 12 and 13 on the bottle are of use in the vulcanizing step, being gripped by 35 the vulcanizer parts and preventing displacement of the bottle during vulcanization. After the parts are united and vulcanized, as above described, and as the flanges are trimmed off smoothly they present a very 40 neat and attractive appearance. These flanges are also of use in the finished bottle as a stiffening medium for the upright funnel, steadyng the same during the filling operation, and they also reinforce the bottle 45 adjacent to the thimble, thus aiding in securely holding the thimble in place.

Inasmuch as the bottle is quite elastic, it is not necessary to have the hole through which the mandrel is removed normally as large as 50 the cross section of the mandrel. A convenient form of mandrel is shown at A in Figs. 9 and 10, this mandrel having a body portion of the shape of the interior of the bottle, a neck portion a^1 (which may be externally corrugated), and a flaring funnel portion a^1 , and one or more wings a^2 to prevent the adhering of the flanges. I have shown one of these blades in full lines, and the other in broken lines, since one of the blades 55 may be omitted, if desired. After the bottle is molded on such a mandrel the elasticity of the bottle allows the mandrel to be readily withdrawn through the neck opening and the communicating slit or slits.

65 If it is desired to have slits through both

shoulders of the bottle on opposite sides of the neck, the slit need extend only part way down the shoulders, as shown in Fig. 2, and such slits, with the central opening, allowing sufficient room for moving the mandrel. If, 70 however, it is desired to make the slit only through one shoulder, it thus extends farther down the shoulder, as shown in Fig. 6, so that the bottle may be easily stripped from the mandrel through the opening provided 75 in this one shoulder and the neck. When one slit is employed, there may be formed at the other shoulder a flange designated 15 in Figs. 5 to 8, this flange being trimmed off so that it eventually has the same shape as 80 the two united flanges 12 on the other side. Thus, whether the slit extends through one shoulder or both shoulders, the finished bottle is substantially the same.

Having thus described my invention, what I claim is:

1. The method of making a bottle of vulcanizable gum compound comprising forming the body and neck portions over a core, the neck portion being formed with a slit in 90 at least one side joining with a slit in the shoulder of the body portion, then withdrawing the core, and uniting the edges of such parts at the shoulder and neck.

2. The method of making a bottle of vulcanizable gum compound comprising molding the body and neck portions over a core, the neck portion being formed with a slit in 95 at least one side joining with a slit in the shoulder, and there being flanges projecting 100 from the neck and shoulder on opposite sides of such communicating slits, then withdrawing the core and uniting the flanges at the shoulder and neck.

3. The method of making a water bottle 105 or similar article of a vulcanizable gum compound comprising making the body portion with two side walls, a split filling funnel, and a split neck, the neck portion or portions uniting the funnel portion or portions 110 with the side walls, and there being one or more pairs of upwardly extending flanges, each flange being integral with one of the walls and with the neck and with the filling funnel, the flanges of such pair or pairs being separated when the parts are molded, whereby a slit is provided communicating 115 with the neck opening, removing the core through such slit and opening, and thereafter intimately uniting the flanges together 120 to close the opening or openings through the shoulder or shoulders of the bottle.

4. The method of making a rubber bottle or similar vessel comprising molding the body and neck portions over a core, the neck 125 portion having an up and down slit through it communicating with a slit at the shoulder of the bottle between the body portions, semi-curing the parts in this condition, removing the core, placing cement on the 130

edges at the slits, and then completing the curing to intimately unite the portions of the neck and shoulder which were on opposite sides of the slit.

5 5. The method of making a rubber bottle or similar vessel comprising molding the body and neck portions over a core, the neck portion being formed with a slit in its side and there being a communicating slit 10 through the shoulder of the bottle, and the neck and sides being formed with flanges or ears adjacent to the slits, there being a flange extending from the shoulder and neck on the diametrically opposite side of 15 the bottle, then removing the core through the opening provided, then intimately uniting the flanges adjacent to the slits, and then trimming off the flanges on both sides of the bottle to present a symmetrical appearance.

6. The method of making a rubber bottle or similar vessel, comprising molding the body and neck portions over a core, the neck portion being formed with one or more side 25 openings therein, permitting withdrawal of the core, and uniting the edges of said parts, after removal of the core, to form the neck.

7. The method of making a rubber bottle or similar vessel, comprising molding the 30 body and neck in a single piece over a core, the neck portion being formed with a side opening communicating with an opening between the body portion and there being extended flanges at the edges thereof, withdrawing the core through the opening thus 35 provided, and then uniting the said flanges to form the neck.

8. The method of making a rubber bottle or similar vessel, comprising molding the 40 body and neck portions in a single piece over a core, the neck portion being formed with separated edges, said separation extending outwardly into the shoulder of the body to form an opening for the withdrawal 45 of the core, and said neck and body having flanges at said edges, withdrawing the core through said opening, and then uniting and vulcanizing the said flanges to form the neck and close the shoulder opening.

50 9. The method of making a rubber bottle or similar vessel, comprising molding the body and neck portions over a core, forming the neck portion with an opening communicating with an opening between the sides of 55 the body, withdrawing the core through the opening thus provided, inserting a thimble within the neck, and uniting and vulcanizing the edges of said parts to form the neck and hold the thimble in place.

60 10. The method of making a rubber bottle or similar vessel, comprising molding the body and neck portions over a core, forming the neck portion separated with flanges

at the edges thereof and a transverse slit in the shoulder, withdrawing the core 65 through the opening provided, and then uniting the flanges and closing the slits by cementing and vulcanizing the edges.

11. The method of making a rubber bottle or similar vessel, comprising molding the 70 body and neck portions over a core, the neck portion being formed in two side parts with an opening therebetween permitting withdrawal of the core, and uniting the edges of said parts, after removal of the core, to form 75 the neck.

12. The method of making a rubber bottle or similar vessel, comprising molding the body and neck portions over a core, the neck portions being formed as two flaps or parts 80 with separated edges extending to the shoulders of the bottle, withdrawing the core through the opening between said parts, and then uniting said edges to form the neck.

13. The method of making a rubber bottle 85 or similar vessel, comprising molding the body and neck in a single piece over a core, the neck portion being formed as two side flaps with extended flanges at the edges thereof, withdrawing the core through the 90 opening between said flaps, and then uniting the said flanges to form the neck.

14. The method of making a rubber bottle or similar vessel, comprising molding the body and neck portions in a single piece over 95 a core, the neck portion being formed as two flaps separated at their edges, said separation extending outwardly into the shoulders of the body, to form an opening for the withdrawal of the core, and said flaps having flanges at said edges, withdrawing the core through said opening, and then uniting and vulcanizing the said flanges to form the neck and close the shoulder opening.

15. The method of making a rubber bottle 105 or similar vessel, comprising molding the body and neck portions over a core, forming the neck portion in two side parts with an opening therebetween, withdrawing the core through said opening, inserting a neck 110 thimble between said side parts, and uniting and vulcanizing the edges of said parts, to form the neck and hold the thimble in place.

16. The method of making a rubber bottle or similar vessel, comprising molding the 115 body and neck portions over a core, forming the neck portion in two separate side flaps with flanges at the edges thereof and transverse slits in the shoulders at the base of said flaps, withdrawing the core through the 120 opening provided by said flaps and slits, and then uniting the flanges and closing the slits by cementing and vulcanizing the edges.

In testimony whereof, I hereunto affix my signature.

MARCELLUS B. CLARKE.
